(57) **CLAIM**

The ornamental design for a combination beverage holder and opener, as shown and described.

DESCRIPTION

FIG. 1 is a top, front, left side perspective view of a combination beverage holder and opener embodying the design, with the combination beverage holder and opener including a main body, a sleeve extending about a lower portion of the main body, and a sealing ring coupled to the top of the main body, and with those features of the combination beverage holder and opener shown in solid lines forming part of the design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a bottom, rear, right side perspective view thereof.

1 Claim, 8 Drawing Sheets
